UNITED STATES PATENT OFFICE.

HAROLD EVERETT BRUNNER AND LORENZO S. COPE, OF PHILADELPHIA, PENNSYLVANIA, ASSIGNEES TO THE HESS-BRIGHT MANUFACTURING COMPANY, A CORPORATION OF DELAWARE.

REDUCING-MILL.

1,211,397.

Specification of Letters Patent. Patented Jan. 9, 1917.

Application filed July 8, 1913. Serial No. 777,813.

To all whom it may concern:

Be it known that we, HAROLD E. BRUNNER and LORENZO S. COPE, citizens of the United States, residing at Philadelphia, in the 5 county of Philadelphia and State of Pennsylvania, have invented certain new and useful Improvements in Reducing-Mills, of which the following is a specification, reference being had therein to the accompanying 10 drawing.

This invention relates to roller mills for reducing or flaking grain, feed, and other materials, of the type employing rotary rolls driven in opposite directions to act on the 15 material fed between them. In mills of this type it is usual to mount one of the rolls so that it may be moved bodily to and from the other roll, and means are provided for adjusting the movable roll to and from its 20 companion roll to control their action on the material. Further, compression springs are provided for holding the movable roll yieldingly in coacting relation to its companion roll so that in the event of the 25 passage of a hard object between the rolls, the movable roll will yield to allow the object to pass. Further, means are provided for effecting the "quick release" of the movable roll, that is its instant movement or separation 30 from the fixed roll, these means being operated when for any purpose it is desired to prevent the rolls from acting on the material passing between them, for instance where the operator might observe that a 35 hard object or foreign substance was about to pass between the rolls. In the operation of mills of this type it is important that in the automatic separation of the rolls, such as would be produced by the passing of a 40 hard object between them, the several compression springs be acted on uniformly without regard to the point in the length of the rolls where the object passes; and it is also important that the means for adjusting 45 the movable roll to and from its companion roll, be of such construction and capable of such operation that an independent adjustment of one end of the roll may be effected relatively to the adjustment of the other end, 50 in order to set the rolls in the exact parallelism. Further it is important that when

the movable roll is adjusted, the adjusting action will not interfere with or disturb the tension of the compression springs.

It is the aim of our invention to provide 55 roll adjusting and controlling mechanism which will meet these requirements, and our invention consists of mechanism for this purpose of improved form and construction operating to permit of the adjustment of 60 the movable roll, to maintain its parallelism with its companion roll, and to control the action of the rolls on the material, without varying the tension of the compression 65 springs, while at the same time in the automatic movement of the movable roll, in the event of the passage of a hard object between the rolls, all of the compression springs will be subjected to uniform compression.

Mechanism operating to effect these objects may be constructed in many different forms, but the preferred embodiment of our invention comprises a movable member having means for controlling its movements, 75 and adjustably connected with the movable roll in such manner that the movable roll may be adjusted at opposite ends independently and relatively to the movable member and to and from its companion roll. In its 80 more specific embodiment, compression springs are mounted to act on the movable member so as to urge the movable roll toward its companion roll; and further, means are provided for positively shifting 85 the movable member transversely in order to move the movable roll away from its companion roll, in effecting its "quick release."

Manifestly the invention may be embodied 90 in other forms and constructions, those represented in the accompanying drawings being merely by way of example. It will be understood therefore that our invention is not limited to any particular form or construction of the parts except in so far as 95 such limitations are specified in the claims.

In the accompanying drawings: Figure 1 is an elevation partly in section of a rolling mill having two sets of reducing rolls and embodying our invention; Fig. 2 is a side 100 view of the mill with one-half of the figure in elevation and the other half in partial

section; Fig. 3 is a horizontal transverse section on the line *a—a* of Fig. 1; and Fig. 4 is a vertical transverse section on the line *b—b* of Fig. 1.

5 Referring to the drawings, in the form of mill shown the two sets or pairs of reducing rolls are the same on both sides of the machine, and inasmuch as our improved mechanism is likewise the same on both sides of 10 the machine as applied respectively to said sets of rolls, a description of the mechanism as applied to one set of rolls will suffice.

The machine embodies a rotary fixed roll 1 and a rotary movable roll 2, the two ends 15 of the latter being mounted respectively in bearings 3, 3 fixed to slides 4, 4 movable horizontally back and forth in fixed guideways 5, 5 sustained by the frame 6 of the machine at opposite sides of the same.

20 7, 7 represent two upright arms which are located respectively at opposite ends of the main frame of the machine adjacent respectively the movable roll bearings 3. The lower ends of these arms are firmly fixed to 25 the opposite ends of a horizontal rock shaft 8, mounted in suitable bearings in the main frame below the movable roll and extending parallel with the axis of the same, the fixed connection of the arms 7 with the shaft 8 30 causing said members to move in unison, and producing in effect a unitary member A movable to and from the roll 1. The movable roll bearings 3 are so connected with the movable member A, that said roll bearings, and consequently the roll 2 carried by 35 them, may be adjusted or moved relatively to said member to and from the companion roll 1. The means for effecting this connection may be in many different forms but we

40 prefer to adopt the particular construction shown in the drawings wherein it will be seen, more particularly in Fig. 1, that the arms 7 are each provided with a circular vertical guideway 9 in which is loosely 45 mounted, to slide up and down, a cylindrical slide or plunger 10 having fixed to its upper end a threaded extension or stem 11 encircled by a nut 12 rotatably sustained by the member 7 but held against endwise 50 movement, and provided with a hand wheel 13 for turning it. At one side the circular guideway 9 is formed with a vertical slot 14 through which extends a horizontal pin 15 fixed to the slide 10, the said pins on

55 opposite sides of the machine having pivoted to them the outer ends of horizontal links 16 whose inner ends are pivoted as at 17 respectively to the two movable roll bearings 3. The links 16 extend at a slight inclination upward from their point of pivotal connection with the roll bearings with the result that they will act with a toggle effect when their outer ends are moved up or down, and will operate to shift the roll 60 bearings back and forth in their guides.

This movement of the links takes place when the hand wheels 13 are rotated, such rotation causing the threaded stems 11 to move endwise in the nuts and causing the cylindrical slides 10 to move up or down in 70 the guideways according to the direction of the rotation of the nuts.

The parts described constitute in effect a roll adjusting mechanism sustained by the movable member A and operatively connected with the roll bearings, the operation of said mechanism moving the movable roll 2 relatively to the member 7. Inasmuch as the roll bearings are independent of each other, they may be independently adjusted 75 by the adjusting mechanisms described, so as to control the positions of the movable roll relatively to the fixed roll and so as to effect and maintain the parallelism of said rolls. While the roll bearings may be adjusted independently relatively to the members A as described, yet when the member A is operated, it will cause the roll bearings to both move in unison and will shift the roll bodily without disturbing the relation 80 of its axis to that of the other roll, this action being due to the fact that the two arms 7 are connected together by the shaft 8 which causes them to move in unison as before described.

90 The two arms 7 of the member A are acted on by compression springs 18, 18 in such manner that the member will be urged yieldingly toward the fixed roll, and through the medium of the adjustable connections between the arms 7 and movable roll bearings, the movable roll will be yieldingly urged toward the fixed roll. The manner of mounting the springs so that they will act as described is shown more particularly in Figs. 1 and 4 where it will be seen that the upper end of each arm 7 is formed with forked arms 19, 19 between which arms is pivoted a collar 20 by means of screws 21, 21 extending through the arms 100 and seated in sockets in diametrically opposite sides of the collar. Within the collar loosely extends a sleeve 22 having a nut or stop 23 threaded on its inner end and engaging the inner side of the collar 20 110 which sleeve is interiorly threaded at its outer end and screwed onto the threaded end of a rod 24 which extends inwardly through the sleeve and has its inner end movably connected with the main frame of the machine in the manner presently to be described. Near its outer end the sleeve is provided with an annular stop or shoulder 115 25 and the spring 18 encircles the sleeve 22 and bears at its outer end against the stop 25 and at its inner end against the collar 20 and in this manner it acts to hold the collar up against the stop 23 with the result that the member A will be yieldingly held by the springs and will yieldingly hold the 120 125 130

roll 2 in coacting relation to the roll 1, which relation is determined by horizontally adjustable set screws 7^a, 7^b, carried by the member A, in position to engage at their inner ends with the frame of the machine.

As a result of the construction described it will be noted that in the event of the accidental passage of a hard object of abnormal size between the rolls, the roll 2 will be pushed back, and through the medium of the adjustable connection between the roll bearings 3 and the movable member A, the latter will be shifted back and both springs 18 will be subjected to the same degree of compression.

The rods 24 are so connected with the machine that they may be moved endwise outwardly manually in effecting the "quick release" or instant separation of the rolls. In the outward movement of the rods, the stops 23 on the inner ends of the sleeves 22 will, by engagement with the collar 20, positively shift the arms 7 outwardly by which movement the movable roll 2 will be shifted away from its companion roll. The outward movement of the rods may be effected in any suitable or appropriate manner but we prefer to adopt a construction by which when the rods are in their normal position, with the rolls in coacting relation, the rolls will be held automatically locked by the reaction of the springs against the annular stop shoulders 25, but may be instantly operated manually to effect their release and to permit them to be moved endwise outwardly. To effect this object the rods are curved at their inner ends in the form of hooks pivoted at their extremities as at 26 to rocker arms 27 fixed to the opposite ends of a shaft 28 to which is attached a hand lever 29 for operating it. The relation of the pivotal connection 26 of the rod with the rocker arm, to the connection of said rocker arm with the shaft is such, that when the parts are in the position shown in Fig. 1, the said pivotal axes will be "passed-center" and any tendency of an outward pull on the rods 24 such as is exerted by the springs 18, will serve to hold the parts locked in the position shown so that it will require a positive movement of the hand lever 29 to the left in order to shift the axes out of their locked relations after which the continued movement of the lever will move the rods 24 endwise outwardly and will thereby correspondingly shift the movable members 7 with the result that the movable roll will be separated from its companion roll.

From the foregoing description it will be noted that the adjustment of the movable roll is in relation to the movable member A and consequently such adjustment will not affect the tension of the compression springs, nor will it disturb in any manner the position of the member A. Furthermore it will

be seen that when the movable roll is automatically separated from its companion roll, as by the passage of a hard object of undue size, the movable roll will maintain its parallelism with its companion roll, the movable arms 7 will be thrown back equally and the compression springs will be uniformly compressed. Further it will be noted that when the arms 7 are thrown back positively by the rods 24 in effecting the "quick release" of the rolls, the parallelism of the latter will be maintained, and the adjustment of the rolls will in no wise be effected, nor will the tension of the springs be changed.

The movement of the roll supports or bearings in unison, and the maintenance of the parallelism of the rolls when the supports are moved, possesses many advantages, one advantage being that in cases where the rolls are equipped with roller or ball bearings, their binding or misalignment will be prevented, which objectionable action would take place unless means were provided for insuring the movements of the bearing supports uniformly and in unison.

The inner rolls 1 of the two sets are fixed as far as any movement to and from the other rolls is concerned, but said rolls 1 are adapted to be adjusted vertically or trammed with relation to the other rolls. This adjustment is effected by means of slides 30, 30 connected with the roll bearings and mounted to move up and down in fixed guides 31, 31 on the frame of the machine at opposite ends. Each of the slides is in the form of two sections 30^a, 30^b connected adjustably together near their upper ends by the fastening bolt 32, and at their lower ends the two sections are supported respectively by vertical adjusting screws 33, 33 tapped in a horizontal bar 34 fixed to the frame, by which means the slides may be moved vertically in their guide ways and one slide section adjusted independently of the other. After the adjustments are made the slides are firmly held in fixed position relatively to the frame by means of the bolts 32 before alluded to and horizontal bolts 34^a, 34^b extending through the slide sections 30^a, 30^b and engaging the frame of the machine. By the construction described the roll 1 may be trammed or adjusted vertically relatively to the other roll, and when the proper adjustment has been effected, the parts may be firmly secured in position.

Having thus described our invention what we claim is:

1. In a mill, the combination of two rolls, one of which is movable to and from the other, movable bearings for the movable roll, a freely movable controlling member for the movable roll, comprising two upright arms connected together in fixed relations to move in unison, an adjustable connection directly

between the arm and its companion bearing, causing the arms to be moved in unison by the movable roll when the latter separates from its companion roll, and permitting of the adjustment of the movable roll relatively to the arms and the companion roll, and springs sustained independently of the movable bearings, and acting on said arms respectively and operating through the medium of said arms, to hold the movable roll yieldingly in coactive relation to its companion roll.

2. In a mill, the combination of a frame, two rolls mounted therein, one of which is movable to and from the other, movable bearings for the movable roll, sustained by the frame, a freely movable controlling member for the movable roll, sustained by the frame, adjustable connections between said controlling member and the respective movable bearings, causing said controlling member to be moved when the movable roll separates from its companion roll, and permitting of the adjustment of the movable roll relatively to the controlling member and to its companion roll, a spring sustained by the frame and acting on the controlling member and operating, through the medium of the controlling member, to hold the movable roll in coactive relation to its companion roll, and means for moving the controlling member in opposition to the spring to quickly separate the movable roll from its companion roll.

3. In a mill, the combination of a frame, two rolls mounted therein, one of which is movable to and from the other, movable bearings for the movable roll, a rock shaft mounted in bearings in the frame and extending parallel with the axis of the rolls, two arms fixed at their ends to said shaft to move in unison, links pivoted at one of their ends to the roll-bearings respectively and movably connected at their opposite ends with the respective arms, adjusting means on the arms acting on the movable ends of the links, and springs sustained independently of the movable bearings and acting on

the arms to hold the movable roll yieldingly in coactive relation to its companion roll. 50

4. In a mill, the combination of two rolls, one of which is movable to and from the other, movable bearings for the movable roll, an upright horizontally movable controlling member for the movable roll, horizontal links pivoted at their inner ends to said bearings respectively, vertically movable slides mounted in the controlling member and jointed to the rear ends of the links, and devices sustained by the controlling member 60 and connected with the slides for adjusting the same vertically.

5. In a mill, the combination of two rolls, one of which is movable to and from the other, movable bearings for the movable roll, a horizontally movable controlling member for the movable roll, adjusting slides sustained by the controlling member and movable relatively thereto at an angle to the movement of the bearings, operative connections between the slides and bearings for moving the latter in one direction when the slides are moved in a different direction, and means sustained by the controlling member for adjusting the slides. 70 75

6. In a mill, the combination of a frame, two rolls, one of which is movable to and from the other, movable supports for the movable roll, a movable member pivotally mounted on the frame, means for controlling the movement of said member, guideways in said movable member, slides movable in said guideways, links pivotally connected with the roll supports respectively, and with said slides, adjusting screws connected with the slides, and rotary adjusting nuts sustained by the movable member and engaging the screws. 80 85

In testimony whereof we have affixed our signatures in presence of two witnesses.

HAROLD EVERETT BRUNNER.
LORENZO S. COPE.
